CABINET CONSTRUCTION

Gregg F. Forsthoefel, Adrian, Mich., assignor to Westinghouse Electric & Manufacturing Company, East Pittsburgh, Pa., a corporation of Pennsylvania

Application January 26, 1938, Serial No. 186,993

4 Claims. (Cl. 62—116)

My invention relates to refrigerator cabinets and has for its object to provide an improved cabinet structure and method of manufacturing the same.

A further object of the invention is to provide an inexpensive refrigerator cabinet which has good heat insulating qualities and a pleasing appearance.

An important object of this invention is to provide an improved metallic refrigerator structure wherein the side and top walls are defined by a pair of sheet metal pieces which may be readily and inexpensively formed.

Another object of the invention is to provide an improved cabinet for a mechanical refrigerating machine having spaced heat absorbing and heat dissipating elements, which cabinet affords ready insertion and removal of said elements as a unit.

It is a further object of the invention to provide an adjustment for the inner shell relative to the outer shell in an insulated cabinet of the character set forth, whereby assembly of the heat breaker or finishing strips may be readily effected.

It is a still further object of the invention to provide a refrigerator cabinet having an insulated door of improved construction.

These and other objects are effected by my invention, as will be apparent from the following description and claims, taken in connection with the accompanying drawings, forming a part of this application, in which:

Fig. 1 is a front view, partially in section, of a domestic refrigerator constructed in accordance with my invention;

Fig. 2 is a vertical sectional view taken along the line II—II of Fig. 1;

Fig. 3 is a plan view of the apparatus shown in Figs. 1 and 2;

Fig. 4 is a sectional view taken along the line IV—IV of Fig. 1;

Fig. 5 is an enlarged sectional view of the cabinet breaker strip and door construction;

Fig. 6 is an enlarged sectional view of a detail employed in the embodiment of my invention disclosed in the preceding views;

Fig. 7 is an enlarged sectional view of some of the elements shown in Fig. 2;

Fig. 8 is an exploded perspective view of the outer shell structure employed in the cabinet; and,

Fig. 9 is a sectional view showing a modification of a detail in the construction of the outer shell.

Reference will now be had to Figs. 1 to 8, inclusive of the drawings wherein I have disclosed my invention applied to a domestic refrigerator including an outer shell 10 and an inner shell 11 spaced from the outer shell 10 by heat insulation 12. The inner shell 11 defines a food storage space 13, cooled in any well known manner, such as, for example, by a conventional refrigerant evaporator 14. The inner shell or liner 11 is open at its front and defines an access opening 15, closed by an insulated door structure 16 hinged at 17 to the cabinet 10 and provided with a latching mechanism (not shown) for maintaining the door closed.

15 The outer shell 10 includes side wall members 19 and 21 having upper portions 22 and 23 bent inwardly, with their meeting edges joined at 24 to define a top wall 25. The portions 22 and 23 of the top wall 25 preferably have the margins of their meeting edges depressed below the plane of the top wall to form a groove 26 extending from the front to the back of the cabinet. The purpose of the groove 26 will be referred to more in detail hereinafter.

20 25 I consider the formation of the outer shell structure an important feature of my invention. The side wall members 19 and 21 may be manufactured from sheet metal and bent to provide the top wall portions 22 and 23 without the use of large and expensive dies. After bending, the meeting edges of the portions 22 and 23 are welded or otherwise suitably joined. As shown, the front and rear edges of the side wall members 19 and 21 are provided with flanges 27 and 27a for a purpose to be referred to hereinafter. The flanges 27 and 27a may be rolled on the members 19 and 21 prior to bending the same or may be 30 35 separate elements as shown at 27b, in Fig. 9. After joining the side wall members 19 and 21, a horizontal or bottom wall 28 is secured to intermediate portions thereof, preferably by welding, and has front and rear flanges 29 and 29a formed thereon. When in position the flanges 29 and 29a are aligned with the respective flanges 27 and 27a of the side and top walls 19, 21 and 25.

40 45 A rear wall 31 is secured in any suitable manner as, by welding, to the flanged portions 27a and 29a of the side walls 19 and 21, the top wall 25, and the horizontal wall 28. The side walls 19 and 21 and the rear wall 31 extend below the horizontal wall 28 for defining a machinery chamber 32 within which a refrigerating machine 33 may be disposed, the latter effecting circulation of refrigerant through the evaporator 14 as described

hereinafter. The bottom portions of the side walls 18 and 21 are preferably tied together by a cross member 38 and the lower end of the rear wall 31, the latter being provided with an opening 34 for the insertion of the refrigerating machine 33 in the chamber 32.

The space between the side walls 18 and 21 defines an opening 35 at the front of the chamber 32 which opening 35 provides access to the refrigerating machine 33 for cleaning. A cover 36 closes the opening 35 and may be secured to the cabinet 16 in any suitable manner. As shown in Fig. 2, the cover 36 may include inturned flanges 37 which engage supporting spring clips 38 suitably secured to the cabinet 16. A base 39 may be provided for supporting the cabinet 16 and encloses a chamber 41 which communicates with the machinery chamber 32 at the front of the cabinet. An air inlet 42 is provided at the rear of the base 39.

As is clearly shown in Fig. 2, the inner shell 11 is provided with an outwardly extending flange 18 formed thereon peripherally of the access opening 15. The flanges 27 and 28 formed on the outer shell structure 10 are in alignment with the flange 18 of the inner shell 11 and in a vertical plane normal to the planes of the side and top walls 18 and 25.

The inner and outer shells 10 and 11 are joined by breaker strips 43 which are disposed peripherally of the access opening 15 and secured to the flanges 18 of the inner shell 11 and the flanges 27 and 28 of the outer shell structure 10. The breaker strips 43 define a portion of the front of the cabinet 16 and are disposed in the vertical plane of the front of the cabinet. The breaker strips 43 are preferably formed of a resinous material that is heat insulating and non-hygroscopic, such as those known under the trade names of "Micarta" and "Bakelite." Any suitable means may be employed for joining the breaker strips 43 to the flange members 18, 27 and 28, but I prefer to employ self-tapping screws shown at 44 in Fig. 5.

In order to position the inner shell 11 and facilitate its assembly in the outer shell 10, I provide adjusting means shown in Fig. 6 and including a screw 45 threaded in a boss 46 that is secured to the inner shell 11, the head of the screw 45 bearing against the rear wall 31. The boss 46 may be considered as part of the inner shell structure. A resilient member, shown as a rubber spacer 47, is disposed between the rear wall 31 and the boss 46 and biases the inner shell 11 forwardly with respect to the rear wall 31. By adjusting the screws 45, the heads of which are accessible at the rear of the cabinet, the inner shell 11 is moved backwardly by the screws or forwardly by the rubber spacer depending upon which way the screws are turned. Accordingly, the flanges 18 of the inner shell 11 are aligned with the flanges 27 and 28 of the outer shell 10. Proper alignment of the shells 10 and 11 and the breaker strips 43 is, therefore, provided and assembly of the cabinet is facilitated.

The refrigerating apparatus which I have chosen to disclose is of the well-known compressor-condenser-expander type. The refrigerating machine 33 includes an enclosed motor compressor unit shown generally at 51 and a condenser 52, the latter being cooled by air translated by a motor driven fan 53. Air for cooling the condenser is drawn from the ambient atmosphere through the opening 42 and cham-

ber 41 in the base 39 and passed in heat exchanging relation with the condenser and compressor unit 51. The heated air is discharged through the opening 34 in the cabinet rear wall 31. A duct structure 54 is preferably secured to the rear wall 31 for conducting the heated air from the opening 34 to a point adjacent the top of the cabinet where it is discharged. Condensed refrigerant is delivered to the evaporator 14 from the condenser 51 by a conduit 55 and vaporous refrigerant passes from the evaporator to the enclosed compressor unit 51 through a conduit 56. An expansion device of the capillary tube type, diagrammatically shown at 57, is connected in the conduit 55 for reducing the pressure of the condensed refrigerant.

The refrigerant conduits 55 and 56 extend upwardly along the rear wall 31 within the duct 54, which protects them from mechanical injury, and thence forwardly through the groove 28 in the top wall 25. At the front side of the cabinet 16 the conduits 55 and 56 extend downwardly behind the breaker strip 43 through slots or openings 58 and 59 formed, respectively, in the top wall 25 and the top side of the inner shell 11. The conduits 55 and 56 extend through the food chamber 13 to the evaporator 14. The insulation 12 above the inner shell 11 is cut away or notched at 61 to accommodate the portion of the conduits 55 and 56 behind the breaker strip 43. A plastic sealing compound may be employed for filling the notch 61 and the slots 58 and 59 for preventing leakage of air into the food chamber 13 and the leakage of moisture into the insulation between the shells 10 and 11. An ornamental cover 62 is provided for covering the groove 28 and the conduits therein.

The cabinet construction described heretofore affords insertion of the refrigerating machine 33, the evaporator 14 and their connecting conduits 55 and 56 into the cabinet as a unit. In inserting the refrigerating apparatus, the refrigerating machine 33 is first inserted through the opening 34 into the chamber 32, it being understood that the duct 54 is removed at this time. The evaporator is maintained in an elevated position and the conduits 55 and 56, which are flexible, are positioned along the back wall 31 and bent to lie in the groove 28. The evaporator 14 is then lowered and inserted into the food compartment 13, the conduits being forced into position within the grooves 58 and 59 and the notch 61 in the insulation 12. The evaporator is then secured in position within the food compartment 13, preferably to the top wall thereof. The plastic sealing compound is applied around the portion of the conduits within the notch 61 for closing the same. After the conduits 55 and 56 and the evaporator are in position, the top breaker strip 43 is secured in position and the cover 62 applied to the groove 28 in the top wall. The duct 54 is also applied to the back of the cabinet.

The insulated door structure includes an outer pan 65, preferably formed of sheet metal, and having an inturned flange 66. An inner panel 67 formed of heat insulating sheet material that is preferably treated or coated to render it substantially non-hygroscopic is secured to the flanges 66 by fastening devices such as, for example, self-tapping screws 68. The panel 67 may be formed of ply wood or pressed fibre material. Heat insulating material 70 is disposed between the panel 67 and the outer pan 65. A resilient gasket 69 is secured to the door peripherally

thereof and engages the cabinet 16 around its access opening when the door is closed.

The gasket 68, as shown best in Fig. 5, is of S formation in transverse section and has a portion 71 thereof lapped or folded around the flange 66, which portion is pierced by the screws 68 when in position. The portion 72 of the gasket 68 may be held upwardly so that the screws 68 may be inserted or removed. When released, the gasket portion 72 returns to the position shown in the drawings.

The door is hinged as shown at 17 to the cabinet, the hinges being secured to the outer shell structure 16 and the outer pan 65 of the door. As the latching mechanism for the door forms no part of the present invention, it has not been shown.

From the foregoing description, it will be apparent that I have provided an improved refrigerator cabinet which may be economically manufactured. The outer shell structure is formed of elements which may be rolled or bent and without the use of expensive dies so that the cost of manufacture is substantially reduced. Furthermore, my invention facilitates the assembly of the inner and outer shell members and provides for readily adjusting one with respect to the other, whereby the breaker strip may be easily attached in its proper position.

My improved cabinet structure is ideally suited for the reception of refrigerating apparatus having spaced evaporating and condensing elements which are unitarily assembled to the cabinet. In this connection it will be apparent that no opening need be provided in the food storage compartment walls through which the evaporator is inserted and which must be closed thereafter. Accordingly, better heat insulating qualities are obtainable with my improved construction than are obtainable with constructions having an opening for the evaporator and closed by a closure member.

As the insulated door structure may be so formed that no part of it extends into the food chamber, substantially all of the space in the latter is available for storage. Furthermore, passage of air to or from the food compartment is reduced when the door is opened and closed as no part of the door displaces air in the food chamber when it is closed.

While I have disclosed a refrigerating machine of the compression type applied to my cabinet structure, it will be understood that it is shown by way of example and that the cabinet structure is equally well suited for receiving other forms of refrigerating machines.

While I have shown my invention in but one form, it will be obvious to those skilled in the art that it is not so limited but is susceptible of various changes and modifications without departing from the spirit thereof, and I desire, therefore, that only such limitations shall be placed thereupon as are imposed by the prior art or as are specifically set forth in the appended claims.

What I claim is:

1. In a refrigerator cabinet structure for housing a refrigerant evaporator and the conduits for conveying refrigerant thereto, the combination of spaced inner and outer shells for defining a food compartment and an access opening therefor, said outer shell having side walls, the upper portions of which are bent inwardly and their meeting edges joined for defining a top wall having a groove formed therein, said evaporator

being disposed within the food compartment, and said conduit for conveying refrigerant to the evaporator being disposed in part within said groove.

5. In a cabinet structure for housing a refrigerating machine, an evaporator and conduits connecting the same, the combination of spaced inner and outer shells having heat insulation therebetween and defining an insulated food compartment and an access opening therefor, a breaker strip disposed in a substantially vertical plane normal to the depth of the cabinet and connecting said inner and outer shells, said outer shell including a top wall having a groove formed therein and including side wall portions, the latter extending below the food compartment and defining a machinery chamber, said evaporator and refrigerating machine being disposed, respectively, in the food compartment and the machinery chamber, said conduits connecting the refrigerating machine and the evaporator having portions thereof disposed within said groove and behind the breaker strip, and a narrow ornamental cover for the portion of the conduits disposed within the groove.

3. In a refrigerator cabinet including vertically-extending front and side walls, the combination of inner and outer shells, said inner shell defining a food storage chamber, a substantially rectangular access opening for the food storage chamber in the front of the inner shell, said inner shell having a flange formed on the top, bottom and sides of the access opening, said outer shell having a concentric rectangular opening provided therein and having a flange formed on the top, bottom and sides thereof spaced from the flange on the inner shell to provide a heat break between said shells peripherally of the access opening, said flange on the outer shell being disposed in a plane parallel to the access opening and being rigid in a direction at right angles to the front wall of the cabinet, a breaker strip of heat insulating material also extending parallel to the front wall of the cabinet, said breaker strip covering the space between the flanges on the inner and outer shells, a door for closing the access opening, and a gasket extending around the top, bottom and sides of said access opening and contacting said door and the front 50 of said cabinet near the side walls thereof for sealing the food storage chamber when the door is closed, said flange on the outer shell extending toward the inner shell a sufficient distance to be in substantial alignment with the gasket in a direction at right angles to the flange on the outer shell when the door is closed, whereby the flange on the outer shell is effective to oppose impacts resulting from door closings.

4. In a refrigerator cabinet including vertically-extending front and side walls, the combination of inner and outer shells, said inner shell defining a food storage chamber, a substantially rectangular access opening for the food storage chamber in the front of the inner shell, said inner shell having a flange formed on the top, bottom and sides of the access opening and extending toward said outer shell, said outer shell having a concentric rectangular opening provided therein and having a flange formed on the top, bottom and sides thereof and extending toward and spaced from the flange on the inner shell, to provide a heat break between said shells peripherally of the access opening, said flanges being disposed in a plane substantially parallel to the access opening, the flange on the outer

shell being rigid in a direction at right angles to the front wall of the cabinet, a breaker strip of heat insulating material extending between said flanges and having the major exposed portion thereof extending substantially parallel to the front wall of the cabinet, said breaker strip covering the space between said flanges, a door for closing the access opening and a gasket extending around the top, bottom and sides of the access opening and contacting said door and the front wall of the cabinet near the side walls

thereof for sealing the food storage chamber when the door is closed, said flange on the outer shell extending toward the inner shell at the top, bottom and sides thereof a sufficient distance to be in substantial alignment with the gasket in the direction at right angles to the flange on the outer shell when the door is closed, whereby the flange on the outer shell is effective to oppose impacts resulting from door closings.

10

GREGG F. FORSTHOEFEL.
